UNITED STATES PATENT OFFICE.

PORTER S. HAMRICK, OF WAUSAU, WISCONSIN.

COMBINED BASIN-FAUCET AND DRINKING-FOUNTAIN.

1,044,648.

Specification of Letters Patent.

Patented Nov. 19, 1912.

Application filed January 8, 1912. Serial No. 670,029.

To all whom it may concern:

Be it known that I, PORTER S. HAMRICK, a citizen of the United States, residing at Wausau, in the county of Marathon and 5 State of Wisconsin, have invented certain new and useful Improvements in Combined Basin-Faucets and Drinking-Fountains, of which the following is a specification, reference being had to the accompanying drawings.

This invention is a combined basin faucet and drinking fountain and consists in the construction, combination and arrangement of devices hereinafter described and claimed.

15 The object of this invention is to provide an improved device of this character which can be used both as a supply faucet for a wash basin or the like and as a drinking fountain and which is extremely cheap and 20 simple in construction and operation, may be readily operated and regulated and is not likely to get out of order.

In the accompanying drawings: Figure 1 is a vertical central sectional view of a combined basin faucet and drinking fountain constructed in accordance with my invention; and Fig. 2 is a detail horizontal sectional view of the same on the plane indicated by the line *a—a* of Fig. 1.

30 The body 1 of the faucet may be of the construction here shown or of any other suitable construction and is illustrated as provided with the usual valve and the stem 2 having the hand-wheel 3 for controlling 35 the valve. From one side of the body of the faucet projects a spout member 4 which is integral therewith.

In accordance with my invention I provide an intermediate spout member 5 which 40 is connected to the spout member 4 by co-acting threaded portions 6 and an outer spout member 7 which also has threaded connection 8 with the intermediate spout member. The latter has a vertical bore 9 which intersects the bore of the spout and in 45 which is a plug 10, mounted for rotation, which plug is provided with an inclined duct 11 and is also provided with a transverse bore 12, which bore 12 may be put into 50 and out of communication with the bore of the spout by partly turning the said plug. The plug is here shown as having an annular shoulder 13 seated on the upper side of 55 the intermediate spout member and as provided at its lower end with a nut 14 which

seats against the under side of the intermediate spout member.

The plug 10 is formed with a tubular handle 15 which extends upwardly and outwardly therefrom and terminates at its 60 outer end in a vertical portion 16, the upper end of the bore of which is covered by a closure 17 here shown as formed integral with the tubular handle, the said closure being provided with a downwardly tapered 65 medially disposed outlet opening which also forms a valve seat 18.

A cap 19 is fitted on the upper end of the tubular handle 15. The base of the said cap is of cylindrical form and is provided 70 with screw threads. The top of the cap is provided with a central threaded opening and also with openings 20, and in the sides of the upper portion of the cap are openings 21. A screw valve 22 has threaded engagement with the central opening in the top of the cap and its lower end is tapered as at 75 23 and disposed opposite the correspondingly shaped valve seat 18. The upper end of the screw valve is provided with a mushroom shaped head 24 which has upwardly converging discharge openings 25 and is also provided in its upper side, at its center, with a kerf 26 for engagement by a screwdriver, whereby the said screw valve may be 80 adjusted as may be required to vary the effective area of the opening in the valve seat 18 and hence control the supply of water to the drinking fountain. A cup 28 of substantially inverted pear shape has threaded 85 engagement with the cap 19 and its chamber 29 incloses and contains the screw valve 22 and also the upper portion of the cap. The top of the cup is provided with a medially disposed depression 30 and also with a central opening 31 to which the center of the mushroom head of the screw valve is presented.

The operation of my invention is as follows. When the tubular handle 15 is turned 100 so as to dispose the bore 12 of the plug 10 transverse and out of communication with the spout 7 and to arrange the duct 11 in communication with the inner portion of the said spout, water from the body of the 105 faucet passes upwardly through the said duct 11, through the tubular handle 15, the opening 18 in the cap 19 and issues from the latter through the openings 20 and 21 into the chamber 29 of the cup, filling the said 110

chamber and also passing upwardly through the openings 35 and the opening 31 into the depression 30, which it overflows, a small quantity of water being always maintained 5 in the said depression and from which a person may readily drink. The flow from the fountain may be regulated, as hereinbefore indicated, by appropriately adjusting the screw valve 22. When it is desired to 10 use the device as a faucet the tubular handle 15 is turned to a position at right angles to the spout of the faucet, thereby cutting off the duct 11 and putting the bore 12 of the plug into communication with the bore of 15 the faucet spout so that water is discharged from the said spout as will be understood.

By providing the upwardly converging discharge opening 25, the water which passes through them serves to lift water 20 that passes out between the head of the screw valve and the mouth of the opening 31 into a cone or bubble whereby the water may be easily taken into the mouth.

Having thus described my invention I 25 claim:

1. A faucet having a turning plug provided with a tube extending therefrom and for communication with the discharge of the faucet, said tube having a closure at its 30 upper end provided with an opening which also forms a valve seat, a cap on the upper end of said tube and having discharge openings above said closure, a valve screw carried by said cap and movable toward and from 35 the valve seat, and a cup connected to said cap and providing a chamber in which the upper portion of the cap and the valve screw are located, the cup having a depression in its upper side and an opening leading to said 40 depression.

2. A drinking fountain comprising a tube having a closure at its upper end provided with an opening which also forms a valve seat, a cap on the upper end of the tube and 45 having discharge openings, a valve screw carried by said cap and movable toward and from the valve seat and a cup connected to said cap and providing a chamber in which

the upper portion of the cap and the valve screw are located, the cup having a depression 50 in its upper side and an opening leading to said depression.

3. A drinking fountain comprising a tube having a closure at its upper end provided with an opening which also forms a valve seat, a cap on the upper end of the tube and having discharge openings, a valve screw carried by said cap and movable toward and from the valve seat, the said valve screw being provided with a mushroom shaped head, 55 and a cup connected to said cap and providing a chamber in which the upper portion of the cap and valve screw are located, the cup having a depression in its upper side and an opening leading to said depression, the head of the valve screw being presented to the opening in the upper side of the cup and provided with discharge openings. 60

4. A faucet having a spout, a turning plug 70 intersecting said spout and having a transverse bore and also provided with an inclined duct arranged at one side of and out of communication with the bore, the bore and the duct being adapted to be alternately 75 arranged in communication with the bore of the spout, a tube leading from said plug and with which the said duct communicates, the said tube being provided at its outer end with an upturned portion terminating in a 80 closure provided with an opening which also forms a valve seat, a cap on the upturned end of the tube and having discharge openings and forming a chamber above the upturned end of the tube with which said discharge openings communicate, a valve screw carried by the cap and movable toward and from the valve seat and a cup connected to the cap and in which the valve screw is 85 located.

In testimony whereof I hereunto affix my signature in the presence of two witnesses.

PORTER S. HAMRICK.
